DECANTER

Raymond F. Loewy, New York, N.Y.

Application November 18, 1957, Serial No. 48,512

Term of patent 14 years

(Cl. D58—8)

Fig. 1 is a front elevational view of a decanter embodying my new design;

Fig. 2 is a side elevational view thereof; and

Fig. 3 is a vertical cross-sectional view thereof taken on the line 3—3 of Fig. 1.

I claim:

The ornamental design for a decanter, as shown.
